(57) **CLAIM**

The ornamental design for a ventilator enclosure, as shown and described.

DESCRIPTION

FIG. 1 is a front perspective view of a ventilator enclosure in accordance with the new claimed design;

FIG. 2 is a front plan view thereof;

FIG. 3 is a rear plan view thereof;

FIG. 4 is a right side view thereof;

FIG. 5 is a left side view thereof;

FIG. 6 is a top plan view thereof;

FIG. 7 is a bottom plan view thereof; and,

FIG. 8 is a rear perspective view thereof.

The broken lines in the Figures depict portions of the ventilator enclosure that form no part of the claimed design.

1 Claim, 8 Drawing Sheets
